ABSTRACT

A detachable magazine for firearms is provided that includes a magazine body having a quad stack region and a transition region and a follower assembly having a follower body, the follower body configured to travel through both the quad stack region and the transition region. The detachable magazine has canted rear walls to accommodate cartridges with a range of lengths.

MAGAZINE FOR FIREARMS

CROSS-REFERENCE TO RELATED APPLICATION

This application is a continuation-in part of and claims the benefit of U.S. patent application Ser. No. 18/087,698 entitled "MAGAZINE FOR FIREARMS" filed Dec. 22, 2022, which in turn is a non-provisional application of and claims the benefit of U.S. Provisional 63/293,030 entitled "MAGAZINE FOR FIREARMS" filed Dec. 22, 2021, the disclosures of which are hereby incorporated by reference in their entireties.

BACKGROUND

It may be desirable to increase the capacity of a detachable magazine without increasing the overall length of such a detachable magazine.

SUMMARY

This Summary is provided to introduce a selection of concepts in a simplified form that are further described below in the Detailed Description. This Summary is not intended to identify key features or essential characteristics of the claimed subject matter, nor is it intended to be used as an aid in determining the scope of the claimed subject matter.

A detachable magazine for firearms is discussed herein that includes a magazine body having a top portion having a feed region formed therein. The magazine body also includes a bottom portion, a left sidewall extending from the top portion to the bottom portion and a right sidewall extending from the top portion to the bottom portion. The right sidewall is spaced apart the left sidewall to define a magazine body recess. The left sidewall and the right sidewall are generally parallel to each other. A central magazine plane is defined between the left sidewall and the right sidewall. The magazine body further includes a transition region in communication with the feed region.

A quad stack region is in communication with the transition region. The detachable magazine further includes a follower assembly having a follower body. The follower body is configured to be received at least partially within the magazine body recess. The follower assembly is configured to travel through both the quad stack region and the transition region and into communication with the feed region. The magazine body further includes a left rear wall extending from the left sidewall toward the central magazine plane, and a right rear wall extending from the right sidewall toward the central magazine plane.

The left rear wall has an outer portion adjacent the left sidewall and an inner portion located closer to the central magazine plane; and wherein the right rear wall has an outer portion adjacent the right primary sidewall and an inner portion located closer to the central magazine plane, wherein a rear wall reference line is defined between the outer portion of the left rear wall and the outer portion of the right rear wall such that the inner portion of the left rear wall is separated from the rear wall reference line thereby defining a left rear wall cant angle, and wherein the inner portion of the right rear wall is separated from the rear wall reference line thereby defining a right rear wall cant angle;

BRIEF DESCRIPTION OF THE DRAWINGS

To further clarify various aspects of some example embodiments of the present invention, a more particular

description of the invention will be rendered by reference to specific embodiments thereof which are illustrated in the appended drawings. It is appreciated that these drawings depict only illustrated embodiments of the invention and are therefore not to be considered limiting of its scope. The invention will be described and explained with additional specificity and detail through the use of the accompanying drawings in which:

10 FIG. 1A illustrates a perspective view of a firearm with a detachable magazine coupled thereto;

FIG. 1B illustrates an exemplary cartridge configured for use in a detachable magazine;

15 FIG. 1C illustrates the detachable magazine of FIG. 1A detached from the firearm;

FIG. 2A is a side view of a detachable magazine;

FIG. 2B is an exploded view of the detachable magazine of FIG. 2A;

20 FIG. 3A is an exploded view of a magazine body shown in FIG. 2B;

FIG. 3B is a cross-sectional view of the magazine body shown in FIGS. 2B and 3A taken along section 3B-3B of FIG. 2B;

25 FIG. 3C is a detail view of a portion of the sectional view of FIG. 3B;

FIG. 3D is a cross-sectional view of the magazine body of FIG. 3A taken along section 3D-3D of FIG. 2B;

FIG. 3E is a cross-sectional view of the magazine body 3A taken along section 3E-3E of FIG. 2B;

30 FIG. 4 is a cross sectional view of the detachable magazine shown in FIG. 2A taken along section 4-4 wherein the detachable magazine is unloaded;

FIG. 5A is a rear view of a follower assembly;

FIG. 5B is perspective view of the follower assembly of FIG. 5A;

FIG. 5C is another perspective view of the follower assembly of FIGS. 5A-5B;

FIG. 5D is a rear of the follower assembly of FIGS. 5A-5C;

40 FIG. 6A is a side view of a detachable magazine in which one cartridge is loaded into the detachable magazine;

FIG. 6B is a cross-sectional view of the detachable magazine taken along section 6B-6B of FIG. 6A in which one cartridge is loaded into the detachable magazine;

45 FIG. 7A is a side view of a detachable magazine in which several cartridges are loaded into the detachable magazine;

FIG. 7B is a cross-sectional view of the detachable magazine taken along section 7B-7B of FIG. 7A in which one round is loaded into the detachable magazine;

50 FIG. 8A is a side view of a detachable magazine in which several cartridges are loaded into the magazine;

FIG. 8B is a cross-sectional view of the detachable magazine taken along section 8B-8B of FIG. 8A in which one round is loaded into the detachable magazine;

55 FIG. 9A is a side view of an empty detachable magazine;

FIG. 9B is a cross-sectional view of the detachable magazine taken along section 9B-9B of FIG. 9A; and

FIG. 9C is a cross-sectional view of the detachable magazine taken along section 9C-9C of FIG. 9A.

DETAILED DESCRIPTION OF SOME EXAMPLE EMBODIMENTS

As will be discussed in more detail hereinafter, a detachable magazine is provided that is configured to store a high number of cartridges relative to its length while being compatible with standard upper receivers. Such a configu-

ration may reduce reloads and a number of detachable magazines associated with a full load out for operators.

FIG. 1A is a perspective view of a firearm 10 having a lower receiver assembly 100 and an upper receiver assembly 120. The lower receiver assembly 100 includes a lower receiver 101. The lower receiver 101 is configured to have the upper receiver assembly 120 coupled thereto. In particular, the upper receiver 120 is configured to be compatible with AR-15/M-4/M-16 standard components (hereinafter referred to as "AR-15 compatible"). In such an example, the engagement between the upper receiver 120 and the lower receiver 100 is well known in the art. Further, the lower receiver 100 is configured to have components and sub-assemblies coupled thereto to interact with the upper receiver assembly 120 when the lower receiver 100 is part of the assembled firearm 10.

As shown in FIG. 1A, the lower receiver 100 includes a magazine well 102 configured to have a detachable magazine 20 coupled thereto and to move out of engagement with the magazine well 102. Accordingly, the magazine well 102 may be configured to allow the detachable magazine 20 to couple thereto while still allowing standard coupling with the AR-15 compatible upper receiver assembly 120.

Further, in at least one example, the lower receiver assembly 100 may be configured to make use of additional standard components that are AR-15 compatible. For example, the lower receiver assembly 100 further includes a trigger assembly 104 and a safety assembly 106. In at least one example, the trigger assembly 104 is configured as an AR-15 compatible trigger while the safety assembly 106 is configured as an AR-15 compatible safety assembly as are both well known in the art.

In another example, the lower receiver 101 is configured to have a buffer tube assembly 108 coupled thereto. However, it will be appreciated that other configurations are possible. For example, the lower receiver 101 may be configured to couple with a bufferless pistol or other configuration without affecting the configuration or operation of the magazine well 102.

When assembled as part of the firearm 10, the lower receiver 101 is configured to facilitate the firing of a nominal round 30 (FIG. 1B). For example, AR pattern rifles are often configured to fire .223 or 5.56 rounds.

FIG. 1B illustrates a nominal round 30, which typically has a projectile 31 and a case 32 containing powder (not shown) and a primer (not shown). The nominal round 30 generally has a central axis 33. A width 34 of the nominal round 30 is defined as the dimension of the widest portion of a nominal round 30 as measured perpendicular to the central axis 33 of the nominal round 30.

Referring now to FIG. 1C, the magazine well 102 defines a magazine receiving recess 110. In at least one example, the magazine well 102 is configured to receive four stacks of cartridges therein, each cartridge (not shown) having a width corresponding to the width 34 (FIG. 1C) of the nominal round 30 (FIG. 1B). As such, at least a portion of the magazine well 102 may have a width that is greater than three times the width 34 (FIG. 1C) of a nominal round (FIG. 1C), such as greater than four times the width 34 (FIG. 1C) of the nominal round 30 (FIG. 1C). Such width may be relatively constant throughout the magazine receiving recess 110 in the magazine well 102.

As a result, the magazine well 102 may be sufficiently wider than two double stacks of cartridges 601 (FIG. 7B) to allow the detachable magazine 20 to have an interior volume, at least a portion of which, is configured to hold four rows of cartridges 601 (FIG. 7B) arranged in two double

rows of cartridges 601 (FIG. 7B). Such a configuration of the lower receiver 101 allows for four rows of cartridges 601 (FIG. 7B) to be placed within the lower receiver 101 such that four rows of cartridges 601 (FIG. 7B) may be placed within the magazine well 102 rather than the two rows typically fit in conventional AR-15 magazine wells.

As shown in FIGS. 1A and 1C, when the detachable magazine 20 is inserted partially into the magazine well 102 to couple the magazine 20 to the lower receiver assembly 100, a portion of the detachable magazine 20 corresponding to an insertion region I (FIG. 1C) will be inserted into the magazine well 102 such that the detachable magazine 20 is inserted up to an insertion depth line 22 as will be described in more detail hereinafter.

One exemplary detachable magazine 20 will be discussed herein after that allows four rows of cartridges 601 (FIG. 6B) to be stored not only within a portion of the detachable magazine 20, but to be stored in a portion of the detachable magazine 20 that is received within the magazine well 102. Further, the detachable magazine 20 described in more detail hereinafter is configured to operate with standard AR-15 pattern upper assemblies. Accordingly, detachable magazines discussed hereinafter are configured to transition from a four row configuration to a two row configuration to allow the detachable magazine 20 to feed a conventional AR-15 pattern upper receiver assembly.

FIG. 2A is a side view of the detachable magazine 20 that generally includes a magazine body 200 and a floor plate 202. As shown in FIG. 3A, the magazine body 200 further includes a rear portion 210, a first side or left portion 220, a second side or right portion 230 that define a cartridge receiving recess 204 (best seen in FIG. 3B). The magazine body 200 further includes a front portion 240 as well as a top portion 250 and a bottom portion 260.

As shown in FIG. 2B, the detachable magazine 20 also includes a follower assembly 500 and a follower spring 502. The floor plate 202 is coupled to the bottom portion 260 of the magazine body. The follower assembly 500 is placed within the magazine body 200 and the follower spring 502 is placed between the follower assembly 500 and the floor plate 202 such that the follower spring 502 is compressed therebetween when the detachable magazine 20 is assembled. Such a configuration causes the follower spring 502 to exert a biasing or lifting force against the follower assembly 500 to urge the follower assembly 500 away from the floor plate 202 and toward the top portion 250 of the magazine body 250.

Referring now to FIGS. 3B and 3C, a central magazine plane 206 is defined between the left portion 220 and the right portion 230. The first or left side portion 220 includes a left primary sidewall 222 and a right primary sidewall 232 that extend away from the rear portion 210 of the magazine body 200. As shown in FIGS. 3B and 3C, the front portion 240 includes a front wall 242.

In the illustrated example, the left primary sidewall 222 and the right primary sidewall 232 are each generally parallel to the central magazine plane 206. An angled left sidewall 224 extends away from the left primary sidewall 222 and intersects with the front wall 242. An angled right sidewall 234 also extends away from the right primary sidewall 232 and also intersects with the front wall 242. The angled right sidewall 234 extends from the right primary sidewall 232 and toward the central magazine plane 206 as shown.

The rear portion 210 includes a rib support rear wall 211 as well as left rear wall 212 and a right rear wall 213. In the illustrated example, the left rear wall 212 intersects with the

left primary sidewall 222 while the right rear wall 213 intersects with the right primary sidewall 232.

The rib support rear wall 211 is coupled to the left rear wall 212 and the right rear wall 213 by shoulders 212A, 212B, but is spaced apart rearwardly from the left rear wall 212 and the right rear wall 213. The rear portion 210 includes a rear ridge portion 214 that extends from the rib support rear wall 211 toward the front portion 240.

The rear portion 210 is configured to angle cartridges (601A, 601B; FIG. 8B) contained in each of the left portion 220 and the right portion 230 toward the central magazine plane 206. Particularly, the rear walls 212, 213 are slanted relative to the central magazine plane 206 rather than being normal thereto. More specifically, as shown in FIG. 3C, the left rear wall 212 has an outer portion 212A adjacent the left primary sidewall 222 and an inner portion 212B located closer to the central magazine plane 206 as shown. Similarly, the right rear wall 213 has an outer portion 213A adjacent the right primary sidewall 232 and an inner portion 213B located closer to the central magazine plane 206.

In the illustrated example, the left rear wall 212 cant rearwardly and thus toward rear wall 211 as the rear wall 212 extends away from the left primary sidewall 222 toward the central magazine plane 206. Similarly, the right rear wall 213 cant rearwardly and thus toward rear wall 211 as the right rear wall 213 extends away the left primary sidewall 222 toward the central magazine plane 206.

According to such a configuration, a rear wall reference line 216 is defined between the outer portion 212A of the left rear wall 212 and the outer portion 213A of the right rear wall 213. As shown in FIG. 3B, the inner portion 212B is separated from the rear wall reference line 216 thereby defining a left rear wall cant angle 217. Similarly, the inner portion 213B is separated from the rear wall reference line 216 thereby defining a right rear wall cant angle 218. In at least one example, the left rear wall cant angle 217 and the right rear wall cant angle 218 are greater than one degree. In at least one example, the left rear wall cant angle 217 and the right rear wall cant angle 218 are each greater than one degree. In at least one example, the left rear wall cant angle 217 and the right rear wall cant angle 218 are each between one and five degrees. In at least one example, the left rear wall cant angle 217 and the right rear wall cant angle 218 are each between two and three degrees.

It will be appreciated that in other examples, the rear walls 212, 213 (and the inner portions 212B, 213B in particular) may be angled relative to the central magazine plane 206 in only parts of the rear portion 210, such as in one or more of the quad stack region Q, the transition region T or the feed region F (all best seen in FIG. 4). In at least one example, the configuration of the rear walls 212, 213 provides the cant, as will now be discussed in more detail.

In at least one example, the outer portion 212A is perpendicular to the left primary sidewall 222 and the inner portion 212B is angled relative to the outer portion 212B by the left rear wall cant angle 217 described above. Similarly, the outer portion 213A in one example is perpendicular to the right primary sidewall 232 and the inner portion 213B is angled relative to the outer portion 213B by the right rear wall cant angle 218 described above. As will be discussed in more detail hereinafter, such a configuration may help facilitate reliable feeding of cartridges (601; FIG. 6B).

In the illustrated example, the magazine body 200 includes a plurality of ribs that guide and stabilize and guide the follower assembly 300 (FIG. 2B) and cartridges as cartridges are loaded into and fed from the detachable magazine 20.

Referring simultaneously to FIGS. 3B, 3C and 3D, these features include at least one central rib portion, such as rear rib 214 or front rib portion 244, which are oriented along the central magazine plane 206. In the illustrated example, front rib portion 244 extends away from the front wall 242 toward the rear rib 214.

Referring still to FIGS. 3B, 3C, and 3D, the magazine body 200 also includes at least one left lateral rib, such as rear left lateral rib 226 or front left lateral rib 228, extending away from left portion 220, such as away from left primary sidewall 222 and toward the central magazine plane 206. These features may also include at least one right lateral rib, such as rear right lateral rib 236 or front right lateral rib 238, extending away from the right portion 230, such as away from the right primary sidewall 232 and toward the central magazine plane 206.

In addition to features configured to engage the follower assembly 500 (FIG. 2B), the magazine body 200 may include stiffener ribs 270, 272 extending from the left primary sidewall 222 and the right primary sidewall 232 respectively as noted in FIG. 3D.

As shown in FIG. 3E, the top portion 250 (FIG. 2B) contains a plurality of follower stop ribs, such as rear left follower stop rib 282 (also shown in FIG. 3A), front left follower stop rib 284 (also seen in FIG. 3A), rear right follower stop rib 292, and front right follower stop rib 294. The rear left follower stop rib 282 and the front left follower stop rib 284 extend away from left portion 220, such as the left primary sidewall 222 as shown in FIG. 3E.

The rear right follower stop rib 292 and front right follower stop rib 294 also extend away from the right portion 230, such as away from the right primary sidewall 232. These features interact with the follower 500 (FIG. 2B) to constrain the travel of the follower 500 within the magazine body 200, as will be discussed in more detail hereinafter.

As shown in FIG. 4, the top portion 250 of the magazine body 200 generally includes feed lips 402, 404 each having an upper end 402A, 404A and a lower end 402B, 402B to thereby define a feed slot 406 therebetween. The top portion 250 also includes upper shoulders 408, 410 that extend from the feed lips 402, 404 to the left portion 220, 230 and to the left primary sidewall 222 and right primary sidewall 232 as shown in the drawings. In the illustrated example, the feed region F is formed from the upper ends 402A, 404A of the feed lips 402, 404 to the lower ends 402B, 404B of the feed lips 402, 404.

In the feed region F, cartridges 601 (FIG. 6B) are stacked on alternating sides of the central magazine plane 206 while in contact with one of the feed lips 402, 404 and an adjacent cartridge 601 (FIG. 6B). Such a configuration moves a cartridge 601 (FIG. 6B) into the feed slot 406 while in contact with either of the feed lips 402, 404 as is known in the art.

Below the feed region R, the transition zone T extends to a point where cartridges 601, (FIG. 7B) are aligned in two rows of double stacked cartridges 601, (FIG. 7B) on opposing sides of the central magazine plane 206 and opposing sides of rear rib 214 and/or the front rib 244 (FIG. 3B). The cartridges 601, (FIG. 7B) are guided and constrained to move between a single alternating double stack to two opposing double stacks in the quad stack region Q by the lateral ribs 226, 228, 236, 238 described above (FIG. 3B). Accordingly, the transition region T is associated with the variable distance of the lateral ribs 226, 228, 236, 238 (FIG. 3B) as will be described in more detail.

Referring simultaneously to FIGS. 3B, 3C, 3D, and 4, the lateral ribs 226, 228, 236, 238 may have a relatively constant

size within the four-stack region Q, which extends from the bottom portion 260 of the magazine body 200 to the upper end Qt of the quad-stack region Q. A lower end of the transition region Tb corresponds to the upper end Qt of the quad-stack region Q. Section 3B is a section view of the lower end of the transition region Tb.

As shown particularly in FIG. 4, a top end 214A of the rear rib 214 extends into the transition region T such that the top end 214A is between the upper end of the transition region Tu and the lower end of the transition region Tb.

With reference again to FIGS. 3B, 3C, 3D and 4, the rear right lateral rib 236 extends a first rear right lateral distance 3361 from the right primary sidewall 232 of the magazine body 200 but transitions from the first rear right lateral distance 3361 (FIG. 3B) at the lower end Tb of the transition region T to a second rear right lateral distance 3362 (FIG. 3D) at an upper end Tu of the transition region T. The second rear right lateral distance 3362 is greater than the first rear right lateral distance 3361.

In at least one example, the front right lateral rib 238 extends a first front right lateral distance 3381 (FIG. 3B) from the primary right sidewall 232 that is relatively constant throughout the first or quad-stack region Q of the magazine body 200 but transitions from the first front right lateral distance 3381 (FIG. 3B) at the lower end Tb of the transition region T to a second front right lateral distance 3382 at the upper end Tu of the transition region T. The second front right lateral distance 3382 is greater than the first front right lateral distance 3381.

In at least one example, the rear left lateral rib 226 extends a first rear left lateral distance 3261 from the primary left sidewall 222 that is relatively constant throughout the first or quad-stack region Q of the magazine body 200 but transitions from the first left right lateral distance 3261 at the lower end Tb of the transition region T to a second rear left lateral distance 3262 at the top of the transition region. The second rear left lateral distance 3262 is greater than the first rear left lateral distance 3261.

In at least one example, the front left lateral rib 228 extends a first front left lateral distance 2381 from the left primary sidewall 222 that is relatively constant throughout the first or quad-stack region Q of the magazine body 200 but transitions from the first front left lateral distance 3281 at the lower end Tb of the transition region T to a second front left lateral distance 3282 at the upper end Tu of the transition region T. The second front left lateral distance 3281 is greater than the first front left lateral distance 3282.

As shown in FIGS. 3B-3D, in at least one example, the first front right lateral distance 3381 is greater than the first rear right lateral distance 3361. It at least one example, the first front left lateral distance 3281 is greater than the first rear left lateral distance 3261. It at least one example, the second front right lateral distance 3382 is greater than second rear right lateral distance 3362. It at least one example, the second front left lateral distance 3282 is greater than the second rear left lateral distance 3262.

Referring again to FIG. 4, the length of the insertion region I as measured from the bottom ends 402B, 404B of the feed lips 402, 404 to the insertion depth line 22 is less than a transition length as measured from the upper end Tu of the transition region to the bottom end Tb of the transition region T.

As also shown in FIG. 4, the rear rib 214 may have a relatively constant thickness through its length, but may end short of the upper end Tu of the transition region T. Similarly, the front rib 244 (FIG. 3B) may have a relatively constant thickness throughout its length. The follower

assembly 500 (FIG. 2B) is configured to engage the various lateral ribs 226, 228, 236, 238 (FIGS. 3B-3D) to facilitate loading of cartridges 601 (FIG. 6B) in the detachable magazine 20 and feeding therefrom.

Referring now to FIGS. 5A and 5B, the follower assembly 500 generally includes a follower body 510 having an upper portion 520 and a lower portion 550 which extend in opposing directions away from a follower reference plane 560. The follower reference plane 560 is perpendicular to a central follower plane 562. The central follower plane 562 is generally aligned with the central magazine plane 206 (best seen in FIG. 4) when the detachable magazine 20 (also best seen in FIG. 4) is assembled.

In the illustrated example, the upper portion 520 extends in a first direction 564 from the follower reference plane 560 while the lower portion 550 extends in a second direction 566 from the follower reference plane 560, the first direction 564 being opposite the second direction 566.

As introduced, the lower portion 550 of the follower body 510 extends from the follower reference plane 560 in the second direction 566. The lower portion 550 includes a spring engagement portion 552 that is configured to be received within or otherwise couple the follower body 510 to a biasing member, such as the follower spring 502 (best seen in FIG. 2B) as described above.

As shown in FIGS. 5A and 5B, the upper portion 520 generally includes a first or left side 522 and a second or right side 524 as well as a front portion 526 and a rear portion 528. A rear left rib slot 530 is defined in the left side 522 and is configured to receive and engage the rear left lateral rib 226 (FIGS. 3B-3E) described above. A front left rib slot 532 is defined in the left side 522 and is configured to receive and engage the front left lateral rib 228 (FIGS. 3B-3E).

A rear right rib slot 534 is defined in the right side 524 and is configured to receive and engage the rear right lateral rib 236 (FIGS. 3B-3E). A front right rib slot 536 is defined in the right side 524 and is configured to receive and engage the front right lateral rib 238 (FIGS. 3B-3E). A rear rib slot 538 is defined in the rear portion 528 and is configured to receive and engage the rear rib 214 (FIGS. 3B-3E) while a front rib slot 539 is defined in the front portion 526 to receive and engage the front rib 244 (FIGS. 3B-3E). Engagement between the various ribs and the slots described above help constrain the movement of the follower assembly 500 as it moves within the magazine body 200.

In addition to containing slots and other features to help constrain the movement of the follower assembly 500, the follower body 510 is further configured to guide and constrain the movement and position of cartridges 601 (FIG. 6B). As previously discussed, the upper portion 520 of the follower body 510 generally includes a first or left side 522 and a second or right side 524. As shown in FIG. 5A, the first or left side 522 has a first support platform 542 offset a first support platform distance 543 away from the follower reference plane 560.

A first support ramp 544 extends from the first support platform 542 away from the follower reference plane 560 and toward the central follower plane 566 as shown in FIGS. 5A and 5D. In at least one example, a top first platform 545 extends further away from the first support ramp 544.

The second or right side 524 has a second support platform 546 offset a second support platform distance 547 away from the follower reference plane 560. A second support ramp 548 extends from the second support platform 546 away from the follower reference plane 560 and toward the central follower plane 562 as shown. The second or right

side 524 may also include a top second platform 549 extending away from the second support ramp 548. The second support platform distance 547 is less than the first platform support distance 543. Though shown as left and right, it will be appreciated that the configuration could be mirrored while remaining equivalent in functional respects.

Referring now to FIGS. 5B and 5C, the lower portion 550 of the follower body 510 may further include one or more bearing support surfaces, such as forward legs 553, 554 and rearward legs 555, 556 that extend away from follower reference plane 560 in the second direction 566. In at least one example, spring engagement portion 552 extends a spring engagement distance 557 from the follower reference plane 560 while the forward legs 553, 554 each extend a forward leg distance 558 from the follower reference plane 560. Similarly, the rear legs 553, 554 each extend a rear leg distance 559 as measured by the follower reference plane 560.

In at least one example, the forward leg distance 558 is greater than the spring engagement distance 557. In at least one example, the rear leg distance 559 is greater than the spring engagement distance 557. In at least one example, both the forward leg distance 558 and the rear leg distance 559 are both greater than the spring engagement distance 555.

Referring again to FIGS. 5A and 5B, the follower assembly 500 includes a dummy round assembly 570. The dummy round assembly 570 is rotatably coupled to the second or right side 524 of the upper portion 520 of the follower body 510. In particular, the dummy round assembly has a link 572 having a first end 572A pivotingly coupled to the second side 524 of the upper portion 520 of the follower body 510, such as at the second support ramp 548 as shown. A second end 572B of the link 572 is also pivotingly coupled to a dummy round 574. The dummy round 574 provides support and positions cartridges for feeding as will be described herein-after at the appropriate point.

The link 572 allows the dummy round 574 to rotate between the position shown in FIG. 5A, which may be described as a first position, and a second position shown in FIG. 5D. Referring now simultaneously to FIGS. 5A and 5D, in the first position shown in FIG. 5A, the dummy round 574 is relatively closer to the central follower plane 562 and further away from the follower reference plane 560 than the dummy round 560 is in the second position shown in FIG. 5D.

Referring again to FIGS. 5B and 5C, the follower assembly 500 further includes a bolt catch mechanism 580. The bolt catch mechanism 580 generally includes a bolt catch 582 and a biasing member 584. In at least one example, the bolt catch 582 is rotatably coupled to the follower body 510. More specifically, a front end 582A of the bolt catch may be rotatably coupled to the follower body 510 while a second end or rear end 582B is allowed to rotate relative to the front or first end 582A.

As shown in FIGS. 5C and 5D, the upper portion 520 of the follower body 510 has a bolt catch recess 586 defined therein to receive at least a portion of the bolt catch 582 to allow the bolt catch 582 to pivot flush with a portion of the upper portion 520 of the follower body 510 when a cartridge 601 is in place. In at least one example, the bolt catch recess 586 (FIG. 5D) is defined in the top first platform 545 on the first side 522. As a result, the bolt catch 582 may be moved flush with the top first platform 545 when a cartridge 601 (FIG. 6B) is in place.

In at least one example, the bolt catch 582 is positioned on an opposing side of the central follower plane 562

relative to the dummy round 574. The bolt catch 582 only extends away from the follower body 510 when feeding of cartridges is complete, not as part of the feeding process. Further, in one example the second end 582B of the bolt catch 582 in the illustrated example extends away from the follower body 510 as the first end 582A is at a relatively fixed position that is offset from the follower reference plane 560.

As will be discussed in more detail hereinafter, the entire follower assembly 500, including the bolt catch mechanism 580 and the dummy round assembly 570, move together as the follower assembly 500 facilitates the loading and feeding of cartridges 601 (FIG. 6B) into and out of the detachable magazine 20 (FIG. 6B).

Referring now to loading of the detachable magazine 20, as shown in the FIG. 4 when the detachable magazine 20 is empty, the follower spring 502 pushes the follower assembly 500 toward the top portion 250 of the magazine body 200 such that the dummy round 574 is in contact with feed lip 404 such that the follower assembly 500 is in the feed region F. In that position, the bolt catch 582 is allowed to rotate to away from the follower body 510 in such a position that it would engage a bolt catch in a firearm if the bolt were cycled, as is well known in the art.

Referring simultaneously to FIGS. 3E, 4 and 5B, at that position, the rear left lateral rib 226, the front left lateral rib 228, the rear right lateral rib 236, and the front right lateral rib 238 extend a maximum amount into the rear left rib slot 530, the front left rib slot 532, the rear right rib slot 534 and the front right rib slot 536 (all shown in FIGS. 5A and 5B) respectively. The rear rib 214 may not extend into contact with the follower body 510 at that position.

As a cartridge 601 is fed into the magazine as shown in FIGS. 6A and 6B, the bolt catch (FIG. 5A) is depressed before or as cartridge 601 engages the follower body 510. As cartridge 601 is fed into the detachable magazine 20, the cartridge 601 contacts the dummy round 574 on one side. The dummy round 574 is constrained from rotation by its contact with the second or right rear lateral rib 236 (FIG. 3B) as well as the contact with the second or right front lateral rib 238 (FIG. 3B). As such, the force acting against the dummy round 574 acts on the follower body 510 in opposition to the biasing force exerted by the follower spring 502 to provide the space for the first cartridge 601 to be contained in the detachable magazine 20. When the loading force is removed, the first cartridge 601 then comes into contact with the feed lip 402 on one side while remaining in contact with the dummy round 574 and top first platform 545 (FIG. 5A).

As shown in FIGS. 7A and 7B, feeding of additional cartridges 601 against the previously fed cartridges 601 and the dummy round 574 to move the additional cartridges 601 into engagement with the feed lips 402, 404 and adjacent cartridges. Contact between cartridges 601 adjacent the dummy round 574 exerts a force on the dummy round 574 to urge the dummy round 574 away from the central magazine plane 206 and toward the right portion 230 of the magazine body 200. As the dummy round 574 is urged toward the right portion 230, the movement of the dummy round 574 is constrained by contact and engagement with the rear right lateral rib 236 and front right lateral rib 238 (both best seen in FIG. 3D).

As seen in FIG. 3D, the rear right lateral rib 236 and the front right lateral rib 238 transition in the distance they extend away from the right portion 230 of the magazine body 200. Referring again to FIGS. 7A and 7B, a configuration allows the dummy round 574 to move toward further

toward right portion 230 until it is in the position shown in FIG. 7B. The dummy round 574 moves from the first position (FIG. 5A) to the second position as it moves through the transition region T due to engagement between adjacent cartridges (601) and the rear right lateral rib 236 and the front right lateral rib 238 (FIG. 3D).

When three or more cartridges are fed into the detachable magazine 20, cartridges 601 will begin engaging central ribs, including rear rib 214 (FIG. 3B) and front rib 244 (FIG. 3B). This engagement. In particular, with reference to FIGS. 5A-5D, the follower assembly 500, including is offset between the left side 522 and right side 523 relative to the follower reference plane 560.

Referring again to FIG. 7B, such a configuration causes the rounds to be slightly offset to one side or the other of the central magazine plane 206 with the offset alternating between slightly toward the left portion 220 or the right portion 230. As cartridges are fed into the detachable magazine 20, they will come into contact with the rear rib 214 (FIG. 3B) and the front rib 244 (FIG. 3B). Depending on their offset as described above, the cartridges 601 are then guided into opposing sides of the central magazine plane 206 and the rear rib 214 (FIG. 3B) where they are doubled stacked within the quad stack region Q.

Accordingly, the detachable magazine 20 is configured to store a relatively high number of cartridges 601 relative to its length. The detachable magazine 20 is also configured to allow for varying lengths of cartridges 601 as well. FIGS. 8A and 8B show the detachable magazine in which several cartridges are loaded into the magazine. FIG. 8B is a cross-sectional view of the detachable magazine 20 taken along section 8B-8B in FIG. 8A.

As previously introduced, the left rear wall 212 and the right rear wall 213 are canted relative the central magazine plane 206. A left-side cartridge 601A, shown on the left side 220 of the magazine body 200, has a case base 602A, a case body 604A, a case shoulder 606A, a case neck 608A, and a projectile 610A. The projectile has a tip 612A. A left side case axis 614A is defined through the left cartridge 601A between the case base 602A and the projectile tip 612A.

Referring now to both FIGS. 3C and 8B, the case base 602A abuts the left rear wall 212 when the cartridge 601A is loaded into the left side 220 of the magazine body 200 such that the left side cartridge 601A, and the left side cartridge axis 614A in particular, is angled toward the central magazine plane 206. The degree to which the left side cartridge axis 614A is angled toward the central magazine plane 206 corresponds to the left rear wall cant angle 217, and in at least one example the left side cartridge axis 614A is equal to the left rear wall cant angle 217. The left rear cant angle 217 allows for a relatively longer left side cartridge 601A than may otherwise fit without interference between the front wall 242 and the left rear wall 212 since by geometry, the hypotenuse of a triangle is larger than either of the other legs.

The right rear cant angle 218 provides the same flexibility for the right side cartridge 601B in similar manner as described with respect to the left side cartridge 601A. As previously introduced, the left rear cant angle 217 and the right rear cant angle 219 may be present throughout the rear portion 210 of the magazine body 200, thereby providing capacity for relatively longer lengths of cartridges 601 throughout the detachable magazine 20.

A right-side cartridge 601B, shown on the right side 230 of the magazine body 200, has a case base 602B, a case body 604B, a case shoulder 606B, a case neck 608B, and a projectile 610B. The projectile has a tip 612B. A right side

case axis 614B is defined through the right side cartridge 601B between the case base 602B and the projectile tip 612B.

Referring still to both FIGS. 3C and 8B, the case base 602B abuts the right rear wall 213 when the cartridge 601B is loaded into the right side 230 of the magazine body 200 such that the right side cartridge 601B, and the right side cartridge axis 614B in particular, is angled toward the central magazine plane 206. The degree to which the right side cartridge axis 614B is angled toward the central magazine plane 206 corresponds to the right rear wall cant angle 218, and in at least one example the right side cartridge axis 614B is equal to the right rear wall cant angle 218. The right rear cant angle 218 allows for a relatively longer right side cartridge 601B than may otherwise fit without interference between the front wall 242 and the left rear wall 212 since by geometry, the hypotenuse of a triangle is larger than either of the other legs.

As shown in FIG. 3E, the top portion 250 (FIG. 2B) contains a plurality of follower stop ribs, such as rear left follower stop rib 282, front left follower stop rib 284, rear right follower stop rib 292, and front right follower stop rib 294. The rear left follower stop rib 282 and the left front follower stop rib 284 extend away from left portion 220, such as the left primary sidewall 222. Similarly, the rear right follower stop rib 292 and the front right follower stop rib 294 extend away from the right portion 230 and from the right primary sidewall 232 in particular.

Referring now to FIGS. 9A-9C, the detachable magazine 20 is configured to provide a reliable stop as the detachable magazine 20 is unloaded. FIG. 9A illustrates the detachable magazine 20 in an unloaded configuration. FIG. 9B is a cross sectional view of the detachable magazine 20 taken along section 9B-9B of FIG. 9A and FIG. 9C is a cross sectional view of the detachable magazine 20 taken along section 9C-9C of FIG. 9A.

As shown in FIG. 9B, left rear follower stop rib 282 includes a lower portion 282A while the right rear follower stop rib 292 includes a lower portion 292A. The lower portion 282A is configured to engage at least one of the first support platform 542 or the first support ramp 544 (FIG. 5A) while the lower portion 292A of right rear follower stop rib 292 is configured to engage at least one of the second support platform 546 or the second support ramp 548, thereby constraining movement of the follower assembly 500 in the feed region F.

Similarly, as shown in FIG. 9C, left front follower stop rib 284 includes a lower portion 284A while the right front follower stop rib 294 includes a lower portion 294A. The lower portion 284A is configured to engage at least one of the first support platform 542 or the first support ramp 544 while the lower portion 294A of right front follower stop rib 294 is configured to engage at least one of the second support platform 546 or the second support ramp 548, thereby stopping constraining movement of the follower assembly 500 in the feed region F.

In each instance, the follower assembly contacts and guides cartridges through the quad stack region and into the transition region. In particular, the follower body travels through both regions and the bolt catch does not extent until the magazine is empty.

As rounds are fed from the magazine, the follower body moves toward the top of the magazine body. As the follower body moves toward the top of the magazine body, the dummy round comes into engagement with the ribs in the

13

transition zone, which move the dummy round toward the central plane and back toward the position described above as the magazine is emptied.

As shown in the figures, the transition zone is shorter than the length of the typical engagement between a magazine and a typical AR-15 magazine well. As such, the magazine is configured to place four rows of cartridges within an associated receiver, rather than just outside the receiver.

What is claimed is:

1. A detachable magazine for firearms, comprising:
a magazine body having a top portion, a bottom portion, a left sidewall extending from the top portion to the bottom portion, a right sidewall extending from the top portion to the bottom portion, the right sidewall being spaced apart from the left sidewall to define a magazine body recess, the left sidewall and the right sidewall being generally parallel to each other, wherein a central magazine plane is defined between the left sidewall and the right sidewall, wherein the magazine body further includes a left rear wall extending from the left sidewall toward the central magazine plane, and a right rear wall extending from the right sidewall toward the central magazine plane; wherein the left rear wall has an outer portion adjacent the left sidewall and an inner portion located closer to the central magazine plane; and wherein the right rear wall has an outer portion adjacent the right primary sidewall and an inner portion located closer to the central magazine plane, wherein a rear wall reference line is defined between the outer portion of the left rear wall and the outer portion of the right rear wall, wherein the left rear wall and is configured such that the inner portion of the left rear wall is separated from the rear wall reference line thereby defining a left rear wall cant angle between the left rear wall and the rear wall reference line, and wherein the right rear wall and is configured such that the inner portion of the right rear wall is separated from the rear wall reference line thereby defining a right rear wall cant angle between the right rear wall and the rear wall reference line.
2. The magazine body of claim 1, wherein the left rear wall cant angle and the right rear wall cant angle are each between 1 and 5 degrees.
3. The magazine body of claim 1, wherein the left rear wall cant angle and the right rear wall cant angle are each between 2 and 3 degrees.
4. The detachable magazine for firearms of claim 1, wherein the top portion of magazine body has a feed region formed therein and wherein the magazine body further includes a transition region in communication with the feed region, a quad stack region in communication with the transition region, and a follower assembly having a follower body, the follower body being configured to be received at least partially within the magazine body recess, the follower assembly being configured to travel through both the quad stack region and the transition region and into communication with the feed region.
5. The detachable magazine of claim 4, further including at least one left lateral rib extending away from the left sidewall and toward the central magazine plane and at least one right lateral rib extending away from the right sidewall and toward the central magazine plane.
6. The detachable magazine of claim 5, wherein the transition region has an upper end and a lower end, wherein the at least one left lateral rib extends a lower left lateral distance from the left sidewall toward the central magazine plane at the lower end of the transition region and transitions

14

to extend an upper left lateral distance from the left sidewall toward the central magazine plane at the upper end of the transition region, the upper left lateral distance being greater than the lower left lateral distance, and wherein the at least one right lateral rib extends a lower right lateral distance from the right sidewall toward the central magazine plane at the lower end of the transition region and transitions to extend an upper right lateral distance from the right sidewall toward the central magazine plane at the upper end of the transition region, the upper right lateral distance being greater than the lower right lateral distance.

7. The detachable magazine of claim 6, wherein the follower body includes a follower reference plane, the follower body further including an upper portion extending away from the follower reference plane in a first direction and a lower portion extending in a second direction away from the follower reference plane, the second direction being opposite the first direction, the upper portion having a left side and a right side as well a front and a rear, wherein at least one left rib slot is defined in the left side and at least one rib slot is defined in the right side, the at least one left rib slot being configured to receive the at least one left lateral rib and the at least one right rib slot being configured to receive the at least one right lateral rib.

8. The detachable magazine of claim 7, wherein the magazine body further includes an insertion region, the insertion region having an insertion length and the transition region having a transition length, the insertion length being greater than the transition region.

9. The detachable magazine of claim 8, wherein a central follower plane is defined between the left side and the right side of the upper portion, the follower assembly further including a dummy round link rotatably coupled to the upper portion of the follower body, the dummy round link being further rotatably coupled to a dummy round, the dummy round being oriented parallel to the central follower plane, wherein the dummy round link is configured to allow the dummy round to move between a first position and a second position, wherein the dummy round is relatively closer to the central follower plane in the first position than in the second position.

10. The detachable magazine of claim 7, wherein the follower assembly further includes a bolt catch mechanism coupled to the upper portion of the follower body, the bolt catch mechanism including a bolt catch and a biasing member, wherein the bolt catch includes a front end and a rear end, the front end of the bolt catch being rotatably coupled to the front of the upper portion of the follower body, while the rear end of the bolt catch is configured to rotate relative to the front end of the bolt catch, the biasing member being configured to exert a biasing force on the second end of the bolt catch urge the second end of the bolt catch away from the follower reference plane.

11. The detachable magazine of claim 10, wherein the bolt catch is positioned on an opposing side of the central follower plane than the dummy round.

12. The detachable magazine of claim 11, wherein the transition region has an upper end and a lower end, wherein the at least one left lateral rib includes a rear left lateral rib and a front left lateral rib, wherein the rear left lateral rib extends a lower rear left lateral distance from the left sidewall at the lower end of the transition region and transitions to extend an upper rear left lateral distance from the left sidewall toward the central magazine plane at the upper end of the transition region, the upper rear left lateral distance being greater than the lower rear left lateral distance and the front left lateral rib extends a lower front left lateral

15

distance from the left sidewall toward the central magazine plane at the lower end of the transition region of the magazine body and transitions to extend an upper front left lateral distance toward the central plane at the upper end of the transition region, the upper front left lateral distance being greater than the lower front left lateral distance and wherein the at least one right lateral rib includes a rear right lateral rib and a front right lateral rib such that the rear right lateral rib extends a lower rear right lateral distance from the right sidewall toward the central magazine plane at the lower end of the transition region and transitions to extend an upper rear right lateral distance toward the central plane at the upper end of the transition region, the upper rear right lateral distance being greater than the lower rear right lateral distance and wherein the front right lateral rib extends a lower front right lateral distance from the right sidewall toward the central magazine plane at the lower end of the transition region and transitions to extend an upper front right lateral distance toward the central magazine plane at the upper end of the transition region, the upper front right lateral distance being greater than the lower front right lateral distance.

13. The detachable magazine of claim **12**, wherein the follower body includes a follower reference plane, the follower body further including an upper portion extending away from the follower reference plane in a first direction and a lower portion extending in a second direction away from the follower reference plane, the second direction

16

being opposite the first direction, the upper portion having a left side and a right side as well a front and a rear, wherein a left rear rib slot and a left front rib slot are defined in the left side of the upper portion of the follower body and a right rear rib slot and a right front rib slot are defined in the right side, left rear rib slot being configured to receive the left rear lateral rib and the front left rib slot is configured to receive the front left lateral rib, the right rear rib slot being configured to receive the right rear lateral rib and the right front rib slot is configured to receive the right front lateral rib.

14. The detachable magazine of claim **13**, wherein the lower portion of the follower body further includes at least one forward leg and rearward leg that extend away from follower reference plane in the second direction and the follower body further includes a spring engagement portion extending away from the follower reference plane a spring engagement distance wherein the at least one forward leg extends a forward leg distance from the follower reference plane and the at least one rear leg extends a rear leg distance from follower reference plane, wherein the forward leg distance and the rear leg distance are both greater than the spring engagement distance.

15. The detachable magazine of claim **14**, wherein the at least one forward leg comprises a plurality of forward legs each extending the forward leg distance and the at least one rearward leg comprises a plurality of rearward legs each extending the rearward leg distance.

* * * * *
